UNITED STATES PATENT OFFICE

2,012,348

INJECTOR

Ireneé P. Pedrick, Philadelphia, Pa., assignor to
 William Sellers & Company, Incorporated,
 Philadelphia, Pa., a corporation of Pennsylvania

Application January 11, 1933, Serial No. 651,075

10 Claims. (Cl. 103—265)

This invention relates to an improvement in injectors such as are used for supplying feed water to steam boilers, as, for example, on locomotives.

5 5 This invention will be applicable to injectors of various types placed either above or below the water supply.

More particularly, this invention relates to an improvement on injectors of the type disclosed in 10 the United States patent to Strickland L. Kneass, No. 1,069,883, dated August 12, 1913; and has for its object more particularly the provision of an injector of the type disclosed by said patent and which will be of increased efficiency and accuracy in service.

15 The injector disclosed by the Kneass patent referred to, and more particularly described with reference to a non-lifting type injector, or one placed below the level of the water supply, comprises the usual water and steam valves, steam nozzle and forcing tubes, the steam and water valves being connected through a lever or yoke to a single operating lever by the manipulation of which the injector may be started and stopped 20 with greater ease and efficiency than in the case of prior injectors where separate manipulation of the water and steam valves was required.

25 More particularly in the Kneass injector referred to the water and steam valves being under pressure respectively of water and steam were so connected to the lever that in its initial movement the water valve opened, with admission of water to the injector, while the steam valve, maintained closed under the steam pressure acting 30 thereon, was opened in the continued movement of the manipulating lever.

35 The Kneass injector, while an advance in the art, has not proved entirely satisfactory due to the fact that on cracking of the steam valve with 40 consequent admission of high pressure steam thereunder, the valve under the influence of the steam pressure, opens faster than the manipulating lever will be normally moved, with the result that the water valve, initially opened, will shut 45 with consequent cutting off of the supply of water. Hence, in the operation of the Kneass injector great care is required to insure against closing of the water valve due to uncontrolled opening, and even where care is exercised, difficulty is encountered in starting the injector.

50 Now, it is the object of this invention to provide an injector of the type indicated, which will be capable of easy and efficient starting by manipulation of a single lever and which, at the same

time, will be accurate and free from the disadvantage pointed out with reference to the injector of the Kneass patent.

Having now indicated, in a general way, the nature and purpose of this invention, I will proceed to a detailed description thereof with reference to the accompanying drawings which illustrate a preferred embodiment and in which:

5 10 Figure 1 is a view, largely in section, of an injector embodying this invention.

Figure 2 is a side view showing a manipulating lever and connections to the water and steam valves of the injector shown in Figure 1.

15 Figures 3, 4 and 5 are views showing details of construction taken on their respectively numbered section lines on Fig. 1.

20 Referring to the several figures *a* is the body or casing of the injector, *b* is the steam inlet and *c* the water inlet, *d* and *e* are steam nozzles and *f* indicates the forcing tubes. *g* is the outlet to 20 the boiler feed line, *h* a line check valve and *i* an overflow outlet from the forcing tubes controlled by an overflow valve *j*.

25 The admission of water to the injector is controlled by a water inlet valve *k*, the stem *l* of which extends through a cylinder *m*, closed at its bottom by a plug *n*, through which the stem passes with a loose fit, and through a stuffing box *o* at the top of the cylinder, to pivotal connection with one end of a crosshead or yoke *p*. 30 Mounted on the stem *l* within the cylinder *m* is a piston *q* positioned so as to be adjacent the lower end of the cylinder when the water valve *k* is closed. The upper end of the cylinder *m* is in communication with the water inlet *c* through 35 a passage *r*, so that water in the cylinder *m* will be discharged ahead of piston *q* when the valve *k* is lifted to operative position without offering any substantial resistance to the opening of the valve. At the same time when the valve *k* is 40 lifted water will be drawn into the cylinder *m*, through the restricted clearance between the stem *l* and plug *n*, and when the valve *k* is moved from open to closed position the water below the piston *q* will be forced out through the clearance between the stem and plug with resistance 45 due to the restricted clearance.

50 The steam nozzle *d* and *e* are closed by means of valves *s* and *t*, respectively, which are carried by a common stem *u*, the valve *t* being of plug form and extending into the upper end of the nozzle *e*. The stem *u* extends through a suitable stuffing box *v* to pivotal connection with the crosshead *p*.

55 The crosshead *p*, which is in effect a lever, is

- secured to a vertically slotted support *w* by means of a pin *x*, or fulcrum, which passes through the slot in the support and to which the crosshead *p* is rotatably secured. To opposite ends of the pin 5 *x* are rotatably secured links *y*, which in turn are secured to the bifurcated end of a lever *z*, the bifurcated end of which is pivotally secured to, or fulcrumed on the support *w*. The lever *z* is connected through a linkage 2, with one arm of a 10 lever 3, pivoted adjacent to a quadrant 4, and the other arm of which is provided with a hand grip and a pawl 5 for engagement with notches provided in the quadrant 4.

The injector, as shown in Figure 1, is provided 15 with means adapted for closing the overflow valve *j* when the line check valve *h* is opened. The means for such purpose, as illustrated, is described and claimed in the United States Letters Patent No. 1,743,684, dated January 14, 1930, to 20 Ireneé P. Pedrick, and comprise a cylindrical chamber 6 formed beneath the line check valve *h* and controlled by a valve 7 connected with lost motion to the line check valve, and from which depends a plug 8 extending into and loosely fitting the chamber 6. The chamber 6 is connected to a chamber 9 above the overflow valve *j* by means of a conduit 10. When the line check valve *h* is opened, pressure is admitted to chamber 6 and passes to chamber 9 acting on the overflow 25 valve to close it. When the line check is closed the pressure in chamber 9 will be discharged, on opening of the overflow valve, through conduit 10 and valve 7, which, as will be observed by reference to Figure 1, may lift slightly independently of the line check valve.

In the operation of the injector in accordance 30 with this invention, it will now be observed that upon manipulation of lever 3, in the proper direction, the crosshead *p* will be lifted through the operation of linkage 2, lever *z* and links *y*. Due to the fact that live steam pressure will be upon 35 the top of valve *t*, the water valve *k* will be more readily lifted than the steam valve and as a consequence the crosshead will be lifted on its pivotal connection with the stem of the steam valve until stopped by the full opening of the water valve. Then the crosshead will lift on its pivotal connection with the stem of the water valve for the opening of the steam valve. When 40 the steam valve is cracked the live steam pressure under the valve will tend to make it fly open, or in other words to move the lever 3 at a rate faster than normal manual manipulation, with the result that a force will operate through the crosshead to close the water valve and consequently prevent starting of the injector. As will now be 45 clear, such force operating to tend to close the water valve during the opening of the steam valve, will be effectively resisted by the necessity for the piston *q* to force water drawn into cylinder *m* around the loose fitting stem *l* in the opening movement of the water valve out of the cylinder through the restricted clearance around the loose fitting stem *l*, in the closing action of the water 50 valve. Thus, the cylinder *m* and piston *q* carried by the valve stem *l* serve as a dash pot to prevent closing of the water valve under the action of the steam valve in opening, while, at the same time, due to the provision of passage *r*, no material 55 resistance is offered to the discharge of water from the cylinder *m* in the opening of the water valve. When it is desired to close the water valve, such may be readily effected over the resistance offered 60 by the dash pot due to the leverage provided from

the lever 3 and its connections with the crosshead *p*.

It will be further noted that in accordance with this invention the manipulating lever 3, which in the case of a locomotive installation will be located 5 in the cab remote from the injector, is connected for the operation of the water and steam valves in a novel manner and through a novel and advantageous arrangement of elements.

It will be understood that I do not intend that 10 this invention shall be limited to the details of construction herein illustrated and described, as it will be obvious to those skilled in the art that various modifications in detail may be made without departing from the invention.

What I claim and desire to protect by Letters Patent is:

1. In an injector, in combination, water and steam valves, stems for said valves, a crosshead pivotally connected to said valve stems, lever 20 mechanism connected to said crosshead and adapted for manipulation whereby said crosshead will be fulcrumed on its connection with the stem of the steam valve to open the water valve and on its connection with the stem of the water valve 25 to open the steam valve and a dash pot connected with the water valve and adapted to resist closure of said valve in the opening movement of the steam valve.

2. In an injector, in combination, water and steam valves, stems for said valves, a crosshead pivotally connected to said valve stems, lever mechanism connected to said crosshead and adapted for manipulation whereby said crosshead will be fulcrumed on its connection with the stem 30 of the steam valve to open the water valve and on its connection with the stem of the water valve to open the steam valve, a cylinder provided with an outlet from its upper end and with a restricted outlet from its lower end surrounding the stem of 35 the water valve, a piston carried by the water valve stem and adapted to travel in said cylinder, said cylinder being adapted to receive and discharge water from the injector supply through said outlets in the travel of said piston on opening 40 and closing of said water valve whereby resistance to the closing movement of said water valve is afforded by the discharge of water through the restricted outlet from the lower end of said cylinder.

3. In an injector, in combination, steam and water valves, stems for said valves, a crosshead pivotally connected to said valve stems, a vertical guide for said crosshead, a hand lever pivotally mounted at a point remote from said injector, 55 a second lever fulcrumed on said injector, a link connecting said second lever with said crosshead intermediate its ends and a linkage connecting said second lever with said hand lever.

4. In an injector, in combination, steam and 60 water valves, stems for said valves, a crosshead pivotally connected to said valve stems, a vertical guide for said crosshead, a quadrant positioned at a point remote from said injector, a hand lever mounted in association with said quadrant and provided with a pawl adapted to engage notches 65 therein, a second lever fulcrumed on said injector, a link connecting said second lever with said crosshead intermediate its ends and a linkage connecting said second lever with said hand 70 lever.

5. In an injector, in combination, valves for controlling the admission of steam and water respectively to the injector, said valves moving to open position in the same direction, means for 75

actuating the water admission valve against steam pressure acting on the steam admission valve, means for creating pressure operative in opposition to closure of said water admission valve and means for actuating said steam admission valve against pressure acting on said water admission valve.

6. In an injector, in combination, a steam valve and a water valve, said valves opening in the same direction, a lever pivotally connected to said valves respectively, means for actuating said lever on its pivotal connection with said steam valve as a fulcrum to open said water valve and pressure means operative on said water valve when it is open whereby said lever may be actuated on its connection with said water valve as a fulcrum to open said steam valve.

7. In an injector, in combination, a water valve, a steam valve, said valves opening in the same direction a lever pivotally connected to said valves respectively means for actuating said lever to open and close said valves and pressure means operative on said water valve in its movement from open to closed position and adapted to resist closure of said valve.

8. In an injector, in combination, water and steam valves, stems for said valves, a crosshead pivotally connected to said valve stems, lever mechanism connected to said crosshead and adapted for manipulation whereby said crosshead will be fulcrumed on its connection with the stem of the steam valve to open the water valve and on its connection with the stem of the water valve to open the steam valve, a cylinder provided with an outlet from its upper end and with a restricted outlet from its lower end, a

piston carried by the water valve stem and adapted to travel in said cylinder, said cylinder being adapted to receive and discharge water from the injector supply through said outlets in the travel of said piston on opening and closing of said water valve whereby resistance to the closing movement of said water valve is afforded by the discharge of water through the restricted outlet from the lower end of said cylinder.

9. In an injector, in combination, a steam valve and a water valve, said valves opening in the same direction, a lever pivotally connected to said valves, means for actuating said lever on its pivotal connection with said steam valve as a fulcrum to open said water valve and a dash pot operatively connected to said water valve and adapted to resist closure of said water valve whereby said lever may be actuated on its connection with said water valve as a fulcrum to open said steam valve.

10. In an injector, in combination, a steam valve and a water valve, said valves opening in the same direction, a lever pivotally connected to said valves respectively, means for actuating said lever on its pivotal connection with the steam valve as a fulcrum to open the water valve and, when the water valve is opened, to actuate said lever on its pivotal connection with the water valve as a fulcrum to open the steam valve and means independent of said lever and actuating means therefor adapted to prevent closure of the water valve in the opening movement of the steam valve, said means being ineffective in the opening movement of the water valve.

IRENEÉ P. PEDRICK.
